Theodore H. Schmitz, ^{INVENTOR}
BY John J. Giedenhein.
ATTORNEY.

UNITED STATES PATENT OFFICE.

THEODORE II. SCHMITZ, OF PHILADELPHIA, PENNSYLVANIA.

DESIGN FOR A GAS-BURNER.

SPECIFICATION forming part of Design No. 22,711, dated August 15, 1893.

Application filed May 1, 1893. Serial No. 472,616. Term of patent 7 years.

To all whom it may concern:

Be it known that I, THEODORE II. SCHMITZ, a citizen of the United States, residing in the city and county of Philadelphia, State of Pennsylvania, have invented and produced a new and original Design for a Gas-Burner, of which the following is a specification, reference being had to the accompanying drawing, forming part thereof.

The leading feature of my design for a gas burner is a base of the form of a leaf with stem and converging veins.

In the drawing: A designates the burner,

B the supply pipe, and C the base which is of the form of a leaf, say that of ivy, the veins D on which converge from the supply pipe B, as the stem of the leaf. The burner projects upwardly from said leaf.

What I claim is—

The design for a gas burner substantially as shown and described.

THEODORE II. SCHMITZ.
